UNITED STATES PATENT OFFICE.

FRANK ZAMECNIK, OF WASHINGTON, DISTRICT OF COLUMBIA.

DESIGN FOR A MUSICAL-INSTRUMENT CASE.

53,327.

Specification for Design.

Patented May 13, 1919.

Application filed March 19, 1919. Serial No. 283,680. Term of patent 14 years.

To all whom it may concern:

Be it known that I, FRANK ZAMECNIK, a citizen of the Republic of Bohemia, residing at Washington, District of Columbia, have invented a new, original, and ornamental Design for Musical-Instrument Cases, of which the following is a specification, reference being had to the accompanying drawings, forming a part thereof.

The figure is a perspective view of a musical instrument case showing my new design.

What I claim is:

The ornamental design for a musical instrument case, as shown.

FRANK ZAMECNIK.
